BALANCED MODULATOR CIRCUIT

Carl Edward Atkins, Evanston, Ill., assignor to
 Tung-Sol Lamp Works, Inc., Newark, N. J., a
 corporation of Delaware

Application September 10, 1942, Serial No. 457,807

9 Claims. (Cl. 179—171.5)

1

My present invention relates to balanced modulator circuits and comprises an improved circuit of this type which will insure substantially complete elimination of the beating input frequencies and of the harmonics thereof, passing only the sum and difference frequencies. The new circuit may be advantageously employed for transmission of sum and difference frequencies of any two input frequencies, but is of particular value for use in radio systems wherein one or the other of the beating input frequencies is so nearly the same as the desired sum or difference frequencies of the output that the selective means in the output circuit of the usual balanced modulator is ineffective to remove the input frequency. The new circuit requires but two tubes, the anodes, screen grids and cathodes of which are parallel connected. The new circuit includes also adjustable means for suppressing harmonic distortion.

The invention is illustrated in the accompanying drawing, of which—

Fig. 1 is a circuit diagram of a balanced modulator circuit embodying the invention and including two input transformers each connected in push-pull with control grids of a pair of tubes;

Fig. 2 is a circuit drawing of a balanced modulator circuit similar to that of Fig. 1 but including one push-pull and one single ended input transformer; and

Fig. 3 is a circuit diagram of a balanced modulator illustrating an embodiment of the invention requiring no push-pull transformers.

The circuit of Fig. 1 includes two multi-element tubes 2 and 4, which may be, for example, of the type known as 6SA7 and two input transformers 6 and 8. The anodes 10 of the tubes 2 and 4 are connected in parallel through a suitable load impedance 12 to a suitable source of positive potential and the screen grids 14 are suitably polarized in the usual manner. The cathodes 16 of the tubes are connected in parallel and grounded through an adjustable resistor 18. Transformer 6 feeds the outer control grids 20 of the tubes in push-pull and the transformer 8 similarly feeds the inner control grids 22 of the tubes.

With the above described circuit, when either pair of grids 20 or 22 is independently energized while the other pair of grids is quiescent, the tubes will supply equal and opposite currents to the load impedance 12 and hence the net output voltage is zero. If, however, both pairs of grids are simultaneously energized, sum and difference frequencies will appear across the output terminals due to the cyclical blending of the input frequencies.

The purpose of the variable resistance 18 in the

2

circuit of the cathodes 16 is to suppress in the output circuit the even harmonics, particularly the second harmonic, of the frequency applied to the inner grids 22. The odd harmonics of the input frequency from transformer 8 are canceled by the push-pull connection which also balances out the fundamental but, with the described circuit, if the inner grids 22 are vigorously driven a possibly troublesome second harmonic would appear in the output circuit if no means were provided for its suppression. The impedance of resistance 18, which it will be noted is not supplied with a bypassing condenser, serves to degenerate this second harmonic, as well as any other even harmonic, since the even harmonic currents are similar for the two tubes. There is no harmonic degeneration for the signal applied to the outer control grids 20 and this no doubt accounts for the fact that the heterodyne frequencies are not in the least affected by the presence of cathode to ground impedance.

The circuit of Fig. 2 differs from that of Fig. 1 primarily in the connection to the inner control grids 22 of tubes 2 and 4. In this arrangement the secondary of a transformer 24 supplying one input frequency is connected across the control grid 22 and the cathode of tube 2 while the inner control grid 22 of tube 4 is grounded. The cathode of tube 2 is grounded through a resistor 26, a variable part of which is in the ground circuit of the cathode of tube 4. As in the circuit of Fig. 1, the outer control grids of tubes 2 and 4 are connected in push-pull relation with the secondary of transformer 6, the anodes 10 are connected in parallel and supplied with positive potential through the load impedance 12 and the screen grids 14 are connected to a suitable source of positive potential.

In the above described circuit, when a signal is applied to the inner grid 22 of tube 2 an alternating current flows in its cathode circuit. As this current is in phase with the grid voltage, any potential drop across the cathode resistor will likewise have the same phase angle as the grid voltage. The application of this voltage drop to the cathode of tube 4 causes the current through tube 4 to be out of phase with the current through tube 2 and accordingly the output currents of the two tubes can be made to cancel when input voltages are applied only to the inner control grids 22. Input voltage applied only to the outer control grids 20 in push-pull produces no component of cathode current because a signal voltage on these grids serves only to determine whether the electron currents proceed on to the anodes or are turned back to the screen grids 14, which prefer-

ably have a positive polarization of 100 volts or more.

The over-all transconductance of the inner control grids is much higher than that of the outer control grids, and hence control of the electron stream is determined by that factor. In the circuit of Fig. 2, as in that of Fig. 1, large signal excursions on the inner control grids produce substantial even harmonic distortion which the degenerative arrangement comprising the resistive impedance in the cathode ground circuit serves to cancel, while similarly large excursions on the outer control grids can be tolerated as but a negligible amount of harmonic distortion is produced. Also, as in the case of the circuit of Fig. 1, sum and difference frequencies are produced by virtue of the differential transconductance which is produced at the heterodyne rate.

In many instances it is of decided advantage to dispense with push-pull transformers, and hence, in Fig. 3, I have shown a balanced modulator circuit embodying the invention in which both input signals may be provided by single-ended sources. In this arrangement, as in that of Fig. 1, two multi-element tubes having their anodes, screen grids and cathodes parallel connected, are employed. In this instance the two tubes 28 and 30 are of the 6A8 variety. The anodes 34 are supplied with positive potential through a load impedance 36 which may be aperiodic or tuned. The parallel connected screen grids 38 are suitably polarized and by-passed to ground by a condenser 40. The parallel connected cathodes 42 are connected to ground through the biasing network 44. One input signal is impressed upon the inner grid 46 of tube 28, condenser 48 and grid leak 50 forming the coupling link to the signal source, and the other input signal is impressed upon the inner grid 52 of tube 30, condenser 54 and grid leak 56 forming the coupling link to this signal source. The anode side-rods or second grids 58 and 60 of tubes 28 and 30, respectively, are suitably polarized in series with respective load resistances 62 and 64. Grid 66 of tube 28 is connected through blocking condenser 68 with grid 60 of tube 30 and grid 70 of tube 30 is similarly connected through a condenser 72 with grid 58 of tube 28. Adjustable grid leaks 74 and 76 provide D. C. return paths for grids 66 and 70, respectively, and also serve for adjusting the system.

In operation of the above described circuit, if energy is supplied from one source only, there will be no net voltage appearing across the load impedance 36. Assume, for example, that grid 52 of tube 30 is energized while grid 46 is quiescent. Current will then flow through tube 30 and a corresponding voltage appears across the load impedance 36. However, grid 60 of tube 30 also takes an alternating plate current of the same signal frequency, and hence an amplified voltage appears across resistor 64, which voltage is 180 degrees out of phase with that on grid 52. Accordingly, this voltage, when applied to grid 66 of tube 28, causes an alternating space current of opposite direction to flow through tube 28, with the result that the voltage appearing across load 36, due to current through tube 30, may be balanced out by that through tube 28 by suitable adjustment of the grid leak 74. Similarly the voltage applied to grid 46 from the other source may be balanced out of the load circuit 36 by adjustment of grid leak 76. Sum and difference frequencies resulting from the interaction of the two input frequencies will, however, appear in the

output circuit. If the load impedance 36 is tuned, the selectivity of the output circuit adds to the attenuation of the input signals already provided by the balancing action of the modulator circuit.

In the circuit of Fig. 3 the grid leaks 74 and 76 have been shown and described as adjustable resistances rather than potentiometers, as it is important that there be no resistance between the second grid of one tube and the fourth grid of the other, that is, between grids 58 and 70 and between grids 60 and 66. These resistances 74 and 76 are preferably of a low value, say, only a few thousand ohms in order to avoid the effects of plate-grid capacity and space-charge coupling, which, if appreciable, would cause the phase angle of the cancellation voltages to depart from 180 degrees sufficiently to impair the balance of the circuit unless neutralized by the employment of conventional means for the purpose. Tuned circuits could be substituted for the load resistors 62 and 64, if desired, but as resistors prove satisfactory and are simpler, they are preferred.

As heretofore indicated, the new balanced modulator circuit, because of the substantial suppression of both input frequencies from the output circuit, is of particular value when the heterodyne frequencies do not differ substantially from one or both of the input frequencies, as in this case the filtering out of one or the other of the input frequencies from the output circuit is not feasible.

I claim:

1. A balanced modulator circuit comprising a pair of multi-element tubes, each having an anode, a cathode and at least two grids, an output circuit to which the anodes of said tubes are parallel connected, an impedance connected to said cathodes so as to have at least a part thereof in the common grid-cathode anode-cathode circuit of each tube, means for exciting one grid of each tube with alternating voltage of one frequency and means for exciting another grid of each tube with an alternating voltage of another frequency, each excited grid of one tube being phased oppositely to its companion grid in the other tube, said tubes each including a third grid and each of said means for exciting the first two mentioned grids of each tube including said third grid of one tube and a connection therefrom to one of the pair of grids of the other tube.

2. A balanced modulator circuit comprising in combination a pair of multi-element tubes each having an anode, a cathode, inner and outer control grids and a pair of screen grids connected together, one of said screen grids being disposed between the outer control grid and the anode, and the other of said screen grids being disposed between the control grids, a load impedance, parallel connections from said anodes to said load impedance, an input transformer having its secondary connected in push-pull with said outer control grids to excite the same with energy of one frequency, a cathode circuit including a resistance to which said cathodes are connected so as to have at least a part thereof in the common grid-cathode anode-cathode circuit of each tube, and means for exciting said inner control grids with energy of another frequency to produce alternating potentials of heterodyne frequencies across said load impedance, said resistance being grounded at one end, and being connected at its other end to the cathode of one tube and at an intermediate point to the cathode of the other tube and said means for exciting said inner grids comprising a transformer having its secondary

connected across the inner grid and the cathode of one tube, the inner grid of the other tube being grounded whereby the voltage drop across said resistance due to current through said first mentioned tube causes the currents through said tubes due to energy supplied by said last mentioned transformer to be out of phase with each other.

3. A balanced modulator circuit comprising in combination a pair of multi-element tubes each having an anode, a cathode and at least three grids, a load impedance, parallel connections from said anodes to said load impedance, a common cathode circuit for said cathodes, means for exciting one grid of one tube with energy of one frequency, means for exciting the corresponding grid of the other tube with energy of another frequency, load circuits for the second grids of each tube, connections including a capacity from the second grid of each tube to the third grid of the other tube, and adjustable grid leaks for said third grids whereby current through one tube due to excitation of its first grid causes out of phase current to flow through the load circuit of its second grid and corresponding voltages to appear on the third grid of the other tube tending to suppress voltages across the load impedance of the frequency of the exciting energy.

4. A balanced modulator circuit comprising in combination two multi-element tubes, each having an anode, a screen grid, a cathode and two control grids, the anodes, screen grids and cathodes of said tubes being parallel connected, push-pull input connections to one control grid of each tube for exciting the same with energy of one frequency, push-pull input connections to the other control grid of each tube for exciting the same with energy of another frequency and a variable resistance connected between ground and said cathodes to cause degeneration of even harmonics of the input frequencies.

5. A balanced modulator circuit comprising in combination a multi-element tube having an anode, a cathode and inner and outer control grids, an input transformer having its secondary connected across said inner grid and said cathode, a resistance grounded at one end and connected to said cathode at the other end, a second multi-element tube having an anode, a cathode and inner and outer grids, the inner grid of said last mentioned tube being grounded and the cathode thereof being connected through a variable part of said resistance with the cathode of said first tube, a second input transformer having its secondary connected in push-pull with the outer grids of said tubes, a load impedance and parallel connections thereto from the anodes of said tubes.

6. A balanced modulator circuit comprising in combination a multi-element tube having an anode, a cathode and inner and outer control grids, an input transformer having its secondary connected across said inner grid and said cathode, a resistance grounded at one end and connected to said cathode at the other end, a second multi-element tube having an anode, a cathode and inner and outer grids, the inner grid of said last mentioned tube being grounded and the cathode thereof being connected through a variable part of said resistance with the cathode of said first tube, a second input transformer

having its secondary connected in push-pull with the outer grids of said tubes, a load impedance and parallel connections thereto from the anodes of said tubes, and a screen grid for each tube adapted to be parallel connected to a source of positive potential.

7. A balanced modulator circuit comprising a pair of multi-element tubes, each having an anode, a cathode, two control grids and a pair of screen grids connected together, one of said screen grids being disposed between a control grid and the anode, and the other of said screen grids being disposed between the control grids, an output circuit to which the anodes of said tubes are parallel connected, at least a part of said impedance being in the common grid-cathode anode-cathode circuit of each tube, a cathode circuit including a resistive impedance to which the cathodes of said tubes are connected, means for exciting one control grid of each tube with alternating voltage of one frequency and means for exciting the other control grid of each tube with an alternating voltage of another frequency, said resistive impedance serving for degeneration of the even harmonics of one of the exciting frequencies.

8. A balanced modulator circuit comprising a pair of multi-element tubes each having a cathode, an anode and at least two control grids, means for exciting in opposite phase one grid of each tube with an alternating voltage of one frequency, means for exciting in opposite phase the other control grid of each tube with an alternating current of another frequency, a common load for said anodes and means common to said cathodes for degenerating the even harmonics of at least one of the exciting frequencies.

9. A balanced modulator circuit comprising a pair of multi-element tubes, each having an anode, a cathode and at least two grids, an output circuit to which the anodes of said tubes are parallel connected, means for exciting one grid of each tube with alternating voltage of one frequency and means for exciting another grid of each tube with an alternating voltage of another frequency, and a variable resistance connected to said cathodes so as to have at least a part thereof in the common grid-cathode anode-cathode circuit of each tube for degenerating the even harmonics of one of the exciting frequencies.
